TYPEWRITING MACHINE

Frederick C. Wendt, Copiague, N. Y., assignor to
 Royal Typewriter Company, Inc., New York,
 N. Y., a corporation of New York

Application January 25, 1945, Serial No. 574,469

2 Claims. (Cl. 197—153)

1

This invention relates to typewriting machines and more particularly to equipment for mounting and feeding thin ribbons, such as carbon paper strips, used for example in manifolding operations.

It has been common, in known constructions of this class, to mount rolls of such ribbon on spindles, axles or the like and to provide some sort of special device for resisting rotation of the axle or the roll core or journal for preventing overthrowing of the rolls and consequent feeding off of surplus ribbon.

An object of the present invention is to provide a simple and efficient ribbon roll mounting which dispenses with the necessity of using such special retarding devices but which nevertheless prevents inertia overthrowing of the ribbon rolls.

Another object of the invention is to provide a roll mounting of the character referred to in which inertia overthrowing is prevented by friction of an exterior surface of the roll, preferably its peripheral surface, resting directly on a smooth, unbroken part of the roll mounting.

Another object of the invention is to provide a roll mounting of the kind referred to which is so constructed as to permit any one of a plurality of ribbon rolls to be removed without disturbing the other rolls.

Another object of the invention is to provide a typewriter ribbon roll mounting adapted to support and prevent inertia overthrowing of ribbon rolls not wound upon cores as well as the more usual core-wound rolls.

Another object of the invention is to provide a ribbon roll mounting of the character referred to in which the retarding or overthrow preventing action decreases as the mass of the roll decreases so that the retarding action will not be unnecessarily great at any time although the inertia of the roll decreases as its diameter and weight are diminished by unwinding of ribbon.

Another object of the invention is to provide a roll mounting of the kind referred to in which a pan or the like for supporting a roll is provided with vertical walls on opposite sides of and immediately adjacent the roll for maintaining the roll properly positioned within the pan.

A further object of the invention is to provide a ribbon roll mounting as referred to above equipped with a top or cover which is so shaped and mounted that when moved to open position it will remain situated close to the pan, resulting in desirable compactness of the whole roll mounting structure.

Other objects will become apparent from a

2

reading of the following detailed description, the appended claims, and the accompanying drawings, in which:

Figure 1 is a fragmentary top view of a typewriter equipped with roll mounting apparatus embodying the invention in a preferred form;

Figure 2 is an enlarged scale rear view of the construction shown in Figure 1, some parts being shown in elevation and others in vertical section;

Figure 3 is a vertical section on the line 3—3 of Figure 2;

Figure 4 is a vertical section on the line 4—4 of Figure 2;

Figure 5 is a fragmentary top plan view of a modified form of latch member and ribbon guide and cooperating parts; and

Figure 6 is a fragmentary elevational view of the latch member and ribbon guide shown in Figure 5 as viewed when looking in the direction of the arrow a in Figure 5, ribbons being shown in section.

Reference is made to the application of John J. Kittel, Serial No. 589,406, filed April 20, 1945, in which is disclosed a typewriter ribbon roll mounting having some characteristics in common with the subject matter disclosed in the present application.

The invention may be embodied in various kinds of manifolding machines or typewriters constructed or equipped for performing manifolding operations or other operations in which it is necessary to feed a ribbon from a roll carried on the machine. Inasmuch as the invention resides in the novel ribbon roll supporting equipment, and in the combination of such equipment with other parts which themselves may be of a conventional nature, the drawings show the known or conventional structure only partially.

Included in the illustrated known construction is a typewriter main frame A on which a carriage generally designated B is mounted for letter spacing and return travel. The carriage B comprises spaced end plates, one of which is shown at 1, connected by carriage frame members, one of which is shown at 2. A platen 3 is mounted on the carriage to be disposed behind the work sheets and carbon strips or ribbons.

Ribbon mounting means R constructed in accordance with the invention is mounted on the rear of the frame A by brackets 4. Strips of ribbon R¹, R², R³, R⁴, R⁵, R⁶, R⁷, R⁸ extending from the ribbon mounting means R are guided and fed along the writing line by suitable mechanism, such for example as the ribbon guiding

and feeding mechanism disclosed in the patent to Myers and Handley 1,890,547. As shown in Figure 1 a bracket 5 mounted on the end plate 1 provides a mounting for a plurality of guide fingers 6, 7, 8, 9, 10 and 11 around which the ribbons R¹—R⁸ are trained respectively as shown in Figure 1 and from which the ribbons extend to a front guide roller 12 also journaled on the bracket 5. All of the ribbons extend from the guide roller 12 in front of the platen 3 along the writing line thereof for being interleaved with work sheets (not shown) in a known manner.

Mechanism for feeding the ribbons along the platen writing line includes a hand lever 13 pivoted as at 14 on the bracket 5. Rockable with the lever 13 is a cam 15 adapted to cooperate with suitable mechanism, for example mechanism as shown in the aforesaid Myers and Handley Patent 1,890,547, for pulling the ribbons along the platen writing line towards the operator's right, that is to the left as viewed in Figure 1. The ribbons may have additional tension imposed on them during operation of the lever 13 by mechanism similar to that shown in the Degener Patent 1,890,563. A pack of leaf springs 16 is mounted on the bracket 5 and each ribbon is extended between two adjacent springs of the pack. When the lever 13 is rocked counter-clockwise, as viewed in Figure 1, the cam 15 actuates a follower roller 17 to rock a lever 18 pivoted as at 19 on the bracket 5. This pulls on a link 20 and spring 21 to rock a lever 22 pivoted on a fixed ear 23. A cam 24 fast with the lever 22 is thereby rocked against a spring arm 25 mounted as at 26 on the bracket 5, thereby pushing the free end of the arm 25 against and compressing the pack of springs 16 and imposing a frictional drag on the ribbons. The drag imposed on the ribbons may be varied by adjusting a screw 27 threaded in a post 28 carried by the bracket 5 and bearing against the pack 16.

In operation, when the end of a typed line is reached the lever 13 is operated to line-space the work sheets and feed the ribbons R¹—R⁸. When a stop 29 on the lever 13 engages a stop portion 30 on the bracket 5 the rocking of the lever is stopped and further pressure on the lever moves the carriage B in the return direction, to the left as viewed in Figures 1 and 2. The ribbons R¹—R⁸ will then be slackened and will assume the positions indicated in dotted lines in Figure 2. When the next line is typed the slack will be taken up, and subsequent operation of the feed lever 13 will draw more ribbon from the ribbon mounting means R.

In accordance with the invention a roll of ribbon is supported by the means R in a novel and very simple manner such that inertia overthrowing of the roll is checked so as to prevent unwinding of ribbon in excess of that actually fed by the ribbon feeding equipment, thereby eliminating danger of entangling of unnecessarily long stretches of unsupported ribbon. The ribbon roll is not journaled to rotate about a fixed central axle in the usual way, but is rested bodily on a support in the nature of a pan, the friction between the pan and an exterior surface of the roll, preferably its peripheral surface, preventing unwinding rotation of the roll except when the ribbon is actually pulled, as by operation of the feeding mechanism.

In the illustrative embodiment of the invention the ribbon mounting means R has capacity for eight rolls R¹—R⁸ from which the ribbons R¹—R⁸ respectively extend, and is formed in two

sections 31 and 32. The section 31 comprises a semi-circular pan carried by a bracket 33 which extends rearwardly from the typewriter main frame A and is braced by a member 34 attached to the main frame A. The pan includes a bottom 35 of semi-cylindrical shape with a straight wall 36 extending upwardly alongside the bracket 33 and terminating just below a horizontal lip 37 at the top of the bracket 33. Partition walls 38 divide the supporting pan into a plurality of compartments for receiving the rolls R¹—R⁶ respectively. The ribbon rolls are supported on the pan's curvingly dished bottom with their axes horizontal and with their lower peripheral portions resting directly on the pan bottom which provides the sole support for the rolls. Ribbons R¹—R⁶ are led from the rolls R¹—R⁶ respectively over the lip 37 to the guide rollers 6—11 as shown in Figure 1. The vertical pan side walls and the vertical partition walls 38 are located immediately adjacent the rolls R¹—R⁶ and maintain the rolls properly positioned and out of contact with each other, thus preventing rubbing of the rolls against each other.

25 A cover 39 for the supporting pan 35 comprises a curved part 40 concentric with the semi-circular pan, a flat part 41 adapted to extend over the lip 37, and side walls 42 pivoted as at 43 on the pan 35, substantially at the axis of the pan semi-circle. 30 Flanges 44 at the sides of the top flat part 41 engage the lip 37 to hold the flat part up enough to provide a slit 45 between the lip 37 and the flat part 41. The ribbons R¹—R⁶ can be fed freely through the slit 45 when the cover 39 is in closed position.

When the cover is swung to open position the curved part will swing under the pan bottom so as to occupy a minimum space.

40 A fastener 46 for holding the cover 39 in closed position includes an ear 47 pivoted as at 48 on the cover 39, a latch part 49 adapted to extend under the pan lip 37, and a U-shaped ribbon guide part 50 which normally guides the ribbons R⁷—R⁸ to extend adjacent and preferably above the point of egress of the ribbons R¹ and R² from the support section 31. Preferably the fastener 46 is provided with a finger piece 51 which may extend from the upper leg of the U-shaped guide part 50.

45 In operation when the feeding equipment pulls on the ribbons R¹—R⁶ to draw fresh ribbon from the rolls R¹—R⁶ the latter will roll upwardly a little on the curvingly dished pan bottom and will slip a little so as to allow ribbon to be drawn off. The friction between the roll peripheries and the pan bottom will prevent inertia overthrowing of the rolls and no surplus ribbon will be unwound. Thus the ribbons R¹—R⁶ extending from the mounting section 31 will not build up to such lengths as could result in tangling and breakage.

50 When the pull on the ribbons is slackened by movement of the carriage B in the return direction the rolls R¹—R⁶ will roll back down the inclined or curved part of the pan bottom 35 to their normal positions shown in Figure 2.

55 The roll support section 32 is carried by a hanger 52 secured to one of the brackets 4 previously referred to. It includes a semi-circular pan-like bottom part 53 with an upstanding extension 54 terminating in a horizontal lip 55. A partition wall 56 divides the pan 53 into two chambers which receive the rolls R⁷—R⁸ respectively. A top 57 comprising a curved part 58 concentric with the semi-circular pan and flat part 59 has sides 60 pivoted as at 61 on the pan 53. Flanges 62 on the top 57 engage the lip 55

to limit closing of the top 57 to a position in which a slit 63 is left for permitting free passage of the ribbons R⁷—R⁸.

The top 57 is equipped with a fastener 64 pivoted as at 65 and having a finger piece 66 and a latch part 67 adapted to extend under the lip 55.

The rolls r⁷ and r⁸ are supported in the pan bottom 53 with their bottom peripheral portions resting directly on the pan bottom which provides the sole vertical support for the rolls. The 10 action of the rolls r⁷—r⁸ in permitting feeding of ribbon and preventing inertia overthrowing is like the action of the rolls r¹—r⁶ previously described.

When it is desired to insert rolls in or remove them from the support sections 31—32, the tops 39 and 57 are turned about their pivots 43 and 61 to uncover the pans 35 and 53. The ribbons r⁷ and r⁸ pass over the top or cover 39 and through the guide part 50 on the fastener 46. When the fastener 46 is swung to releasing position, the ribbons r⁷—r⁸ extending through the guide part 50 are displaced laterally to one side of the pan 35 so as not to interfere with removal of a roll from the pan 35. Thus, in one operation, the fastener 46 is released preparatory to opening the cover 39 and the ribbons r⁷ and r⁸ are moved substantially clear of the pan 35 preparatory to inserting a new roll or rolls in the pan 35.

Inasmuch as no axle or pintle extends centrally through the rolls r¹—r⁸, any of the rolls may be removed at any time without disturbing the other rolls. The diminishing weight of each roll resulting from unwinding of ribbon causes the frictional drag or resistance to slipping on the supporting pan to decrease in proportion to the decrease in the tendency for the roll to overthrow. Thus unnecessarily great drag on the ribbons is prevented and danger of breaking is minimized.

In the construction shown in Figures 5 and 6 the top 39 is adapted to be held in pan-closing position by a modified form of combined latch and ribbon guide member generally designated 68. The member 68 includes an ear 69 pivoted as at 70 to the top 39 and part 71 bent down at a right angle to the ear 69 and being formed with a finger piece 72. A latch part 73 is adapted to project under the lip 31 for holding the top or cover 39 in its closed position and a U-shaped 45 guide part 74 is adapted to overlie the slit 45 for guiding the ribbons R⁷ and R⁸. When the member 68 is swung to the position shown in dotted

lines in Figure 5 the cover or top 39 will be released and the ribbons R⁷ and R⁸ will be displaced substantially from above the pan 35.

It will be observed that the pan bottoms 35 and 53 are both smooth, unbroken and free from joints in their lower portions on which the ribbon rolls are supported. Consequently the friction between the rolls and the pans will be substantially constant over all of the roll supporting surface portions, which assures smooth, steady slippage between the rolls and the pans.

The apparatus disclosed embodies the invention in a preferred form but it will be understood that changes may be made in the construction and arrangement of the parts without departing from the invention as defined in the claims.

I claim:

1. In a typewriting or like machine, a platen; and means for mounting two ribbon rolls from which two ribbons respectively extend for being guided and fed along the printing line of said platen, said mounting means including two sections arranged in tandem so that the ribbon from one section extends past the other section, a cover mounted on said other section to move to open position to enable insertion and removal of a ribbon roll and to closed position, and a guide on said cover adjacent the point of egress of ribbon from said other section and through which ribbon from said one section is trained for being maintained in predetermined relationship to the ribbon extending from said other section.

2. In a typewriting or like machine, a platen; and means for mounting two ribbon rolls from which two ribbons respectively extend for being guided and fed along the printing line of said platen, said mounting means including two sections arranged in tandem so that the ribbon from one section extends past the other section, a cover mounted on said other section to move to open position to enable insertion and removal of a ribbon roll and to closed position, a fastener for securing said cover in closed position, and a guide part on said fastener through which ribbon from said one section is trained, said fastener being movable to a fastening position in which said guide part constrains the ribbon from said one section to extend over said cover and to a released position in which said guide part deflects said ribbon towards one side of said cover to provide easy access to said other section when said cover is moved to said open position.

FREDERICK C. WENDT.
